B. HINKLEY.

Grain Mill.

Patented Mar. 10, 1834.

Benjamin Hinckley of Fayette Kennebec Co: Maine
Letters Patent.

The structure referred to in this Letters Patent and making part of the same, containing a description in the words of the said Benjamin Hinckley himself of his improvement in the mill for cracking or grinding corn and other grain by hand or other power.

To all to whom these presents shall come:

Be it known that Benjamin Hinckley of the town of Fayette in the County of Kennebec and State of Maine has invented a new and useful improvement in a mill for cracking or grinding corn or other grain by hand or other power and that the following is a full and clear description of the construction and operation of the said machine as invented or improved by me. The size for hand power is as follows. First. A frame made of planks one and a half inch thick. The top end is fifteen inches wide and thirty two inches high. The side pieces of said frame is at the bottom about thirty six inches long, at at the top about thirty six inches long of suitable width to give strength to the frame. Second. A cylinder made of German or Cast Steel, two and half inches in diameter and the grinding part about twelve inches long. The surface of which is cut or indented in form of a rasp or grater. The two ends of said cylinder or shaft are one inch in diameter and one and a half inch long turned perfectly true to run in the boxes and said cylinder or shaft extends at each end about one and half inch further which last inch and half at each end is turned down to three quarters of an inch in diameter, making the whole cylinder or shaft of solid steel about eighteen or nineteen inches long. This cylinder is placed upon or across the frame running upon cast iron or composition Boxes, which boxes are placed upon and half inserted into the top side pieces of the frame. One end of said cylinder shaft projecting beyond the frame is for a balance or fly wheel. The other end is for a spur or cog wheel. which spur wheel is about five inches in diameter and one inch thick and made of cast iron. Third. The grinding part of said cylinder or roller never flat surface a plate of wrought iron about one and quarter inch wide and about a quarter inch thick and one length as the grinding part of the cylinder. This plate of iron is concave or hollowed to a block of wood about thirteen inches long, three inches wide and one and a half inch thick which

Mar. 10, 1834

is placed by the side of the cylinder, the iron surface or plate being nearly perpendicular by the side of this block is placed another block of same dimensions there which passes his screws for the purpose of quaging the flat iron surface to and from the cylinder. From the parallel with the cylinder and about seven inches from it is placed an iron shaft about one inch in diameter and about twenty inches long on one end of which is placed the larger spur or speed wheel often inches diameter and one inch thick this spur wheel runs into and projects the larger spur wheel on the end of the cylinder and on the end of the said iron shaft is placed the counter or power wheel. The iron shaft also runs upon cast iron or composition boxes placed upon and half inserted into the top side pieces of the frame which shaft and cylinder are confined by cap pieces, screws and bolted upon the top of said frame. A suitable hopper is placed upon the top of the frame to pass the corn or grain between the cylinder and flat iron surface and so in proportion for machine of greater power. I claim in this machine as my invention the particular form of the solid steel cylinder, shaft and the indenture or rasping surface made upon the grinding point of the same and the flat surface of iron and the manner of screwing and quaging the same to and from the cylinder shaft.

End.
